[57] CLAIM

The ornamental design for a combined video camera and photographic printer, as shown and described.

DESCRIPTION

FIG. 1 is a front elevational view of a combined video camera and photographic printer showing my new design;

FIG. 2 is a side elevational view thereof;

FIG. 3 is a side elevational view of the side opposite that shown in FIG. 2.

FIG. 4 is a rear elevational view thereof;

FIG. 5 is a top plan view thereof;

FIG. 6 is a bottom plan view thereof;

FIG. 7 is a top plan view as seen in the direction of line 7—7 of FIG. 1;

FIG. 8 is a front perspective view thereof; and

FIG. 9 is a rear perspective view thereof.

FIG. 1

FIG. 2

FIG. 3
